FOOD STORING AND DISPENSING VEHICLE

Abraham S. Levin, Philadelphia, Pa.

Application December 21, 1956, Serial No. 44,299

Term of patent 14 years

(Cl. D14—3)

The drawing is a perspective view of a food storing and dispensing vehicle embodying the design.

The back of the vehicle is conventional and the right side is identical with the left side.

What I claim is:

The ornamental design for a food storing and dispensing vehicle, as shown and described.
